UNITED STATES PATENT OFFICE.

CHARLES GILBERT HAWLEY, OF CLEVELAND, OHIO, ASSIGNOR TO LOCOMOTIVE FIRE-
BOX COMPANY, OF CHICAGO, ILLINOIS, A CORPORATION OF DELAWARE.

LOCOMOTIVE BOILER.

Application filed April 8, 1926. Serial No. 100,481.

This invention relates to improvements in locomotive boilers and its consists of the matters hereinafter described and more particularly pointed out in the appended claims.

5 The primary object of the invention is to provide a simple and efficient means directly associated with the crown sheet of the boiler which operates in that part of the fall in boiler water level, initially uncovering or 10 exposing a part of said crown sheet adjacent the flue sheet, to limit the same to an area which is safe in practice but will act to permit a leakage of a small amount of steam into the firebox, sufficient to be observed in the 15 stoking of the firebox, thereby informing the fireman of the actual water level in the boiler, irrespective of the level indicated by the usual gages.

A further object of the invention is to provide in the crown sheet, between predetermined rows of stay bolts, channels which extend longitudinally of the crown sheet and act as the water level falls to uncover the high spot or head of the crown sheet at the 25 flue sheet end, to limit such spot or area to one of small dimensions and about the stay bolts of which, steam escapes into the firebox to be observed by the one stoking the firebox.

These objects of the invention as well as 30 others, together with the many advantages thereof will more fully appear as I proceed with my specification.

In the drawings:—

Fig. 1 is a vertical longitudinal sectional view through the firebox end of a locomotive boiler embodying my invention.

Fig. 2 is a vertical transverse section through the same as taken on the line 2—2 of Fig. 1.

40 Fig. 3 is a detail horizontal sectional view on an enlarged scale as taken on the line 3—3 of Fig. 1.

Fig. 4 is an enlarged detail view of parts shown in Fig. 2 and which will be more fully 45 referred to later.

Referring now in detail to that embodiment of the invention illustrated in the accompanying drawings:—1 indicates the back or door sheet of the firebox and 2 indicates 50 the flue sheet thereof and forming a continuation of the flue sheet, is the inside throat sheet 3. The sides of the firebox are formed by the side sheets 4—4 and the top of the firebox is provided by the transversely arched 55 or curved crown sheet 5 which merges into

the firebox side sheets 4—4. Said side sheets and crown sheet extend between and are connected at their ends to the back sheet 1 and flue and throat sheets 2 and 3 respectively the crown sheet being inclined upwardly from 60 the back sheet toward the flue sheet so that its highest point or head 6 is at the flue sheet end thereof.

The wrapper of the boiler includes a roof sheet 7, a back head 8, outer firebox sheets 9—9 and an outer throat sheet 10 together with a boiler shell 11, all in the manner well known. The front and rear water legs 12 and 13 and the side water legs 14—14 are all closed at the bottom by a mud ring 15, while 70 the bottom of the firebox is formed by the grate indicated by the dotted line 16 in Fig.

1. In the back head and back sheet respectively is formed the fuel door opening 17 and extending forwardly from the flue sheet 75 2 are the flues or tubes 18 through which the products of combustion from the firebox are drawn to the smoke box at the front end of the boiler (not shown) in the manner well known. The roof sheet and crown sheet are 80 connected by the usual stay bolts 19, as are the side sheets 4 and 9, throat sheets 3 and 10 and back sheets 1 and 8 respectively. The construction just described is typical of that 85 type of locomotive boiler now in general use and need not be described in greater detail.

In locomotive practice, the usual water level desired to be maintained, is such as to keep the crown sheet submerged at all times. However due to the amount of water generated into steam for the intended purpose 90 of the locomotive, the water level falls. Gage glasses in the cab are intended to indicate the levels of the water but such devices are often inaccurate, not always due to any faulty construction therein, but to certain boiler conditions such as surgings and foamings which will produce in the gage glasses, levels which do not correspond to the actual water level in the boiler. When the real water level falls 95 below that point, good locomotive practice demands be maintained, the first part of the crown sheet to be uncovered thereby, is that point of highest elevation and which point is usually the head 6 of the crown sheet, which 100 is located in the longitudinal median plane of the transversely curved crown sheet. Such a level as will uncover or expose this part of the crown sheet is best indicated at 20 in Figs. 1 and 4.

To maintain or limit the uncovered or dry area of the crown sheet to one of as small dimensions as possible, I form in the crown sheet, longitudinal V shaped channels 21—21 5 one on each side of and adjacent the median plane of the crown sheet. The said channels decrease in width and depth from the front to the rear and are of the greatest width and depth where they open through the top edge 10 of the flue sheet, the bottom of said channels being arranged in a horizontal plane.

As the water level recedes so as to uncover the head end of the crown sheet, where it is highest in elevation, the lateral edges of said 15 uncovered and dry spot will be defined by portions of the channels which are filled with water as best shown in Fig. 4. The front of said dry spot is defined by the front edge of the crown sheet and the rear edge of the 20 dry spot is defined by the water's edge as best shown in Fig. 3 so that the dry spot 22 is one of such area as may be uncovered with safety. That part of the crown sheet, thus 25 uncovered becomes excessively hot and will flex inwardly of the firebox thus pulling away from the stay bolts 19 within said area so that steam will escape in small quantities about said stay bolts into the firebox. Such 30 a condition is instantly visualized by the fireman who will feed more water into the boiler to submerge the crown sheet head. With the entire crown sheet submerged the danger of complete fracture thereof is eliminated but 35 at the first opportunity.

It is pointed out that the channels in the crown sheet not only thus act to define or limit the sides of said dry area but at the same time act to rigidify the crown sheet 40 as is apparent.

While in describing my invention, I have

referred to certain details of construction as well as form and arrangement of parts thereof, I do not wish to be limited thereto except as may be pointed out in the appended 45 claims.

I claim as my invention:—

1. A locomotive boiler embodying therein, a firebox including a crown sheet and a flue sheet, said crown sheet being formed to 50 provide channels therein which are deeper at the front ends where they open through the top portion of the flue sheet.

2. A locomotive boiler embodying therein, a firebox including a crown sheet and a flue 55 sheet, said crown sheet being formed to provide channels therein which decrease in width and depth rearwardly from the flue sheet, said channels opening through the top portion of the flue sheet.

3. A locomotive boiler embodying therein a firebox including a stay bolted crown sheet and a flue sheet, said crown sheet being formed to provide longitudinal channels therein between adjacent rows of stay bolts 60 which channels decrease in width and depth from the flue sheet rearwardly, said channels opening through the top portion of the flue sheet.

4. A locomotive boiler embodying therein 70 a firebox including a crown sheet and a flue sheet, said crown sheet being formed to provide relatively shallow channels therein which are deeper at the end adjacent the flue sheet than at the opposite end whereby a 75 portion of the crown sheet is isolated when the water reaches a predetermined low level to act as a low water telltale.

In testimony whereof, I have hereunto set my hand, this 5th day of April, 1926.

CHARLES GILBERT HAWLEY.
